US0D1096396S

(12) United States Design Patent (10) Patent No.: US D1,096,396 S
(45) Date of Patent: * Oct. 7, 2025

(54) PACKAGING CARTON

(71) Applicant: TruSkin Partners, Inc., Seattle, WA (US)

(72) Inventors: Sean Beckner, Seattle, WA (US); Erica Reh, Seattle, WA (US); Mark Chester, Seattle, WA (US); Doug Squyres, Seattle, WA (US)

(73) Assignee: TruSkin Partners, Inc., Seattle, WA (US)

() Term: 15 Years

(21) Appl. No.: 29/958,342

(22) Filed: Aug. 19, 2024

Related U.S. Application Data

(63) Continuation of application No. 29/911,907, filed on Sep. 11, 2023, now Pat. No. Des. 1,039,377, which is a continuation of application No. 29/782,559, filed on May 7, 2021, now Pat. No. Des. 1,011,187.

(57) CLAIM

The ornamental design for a packaging carton, as shown and described.

DESCRIPTION

FIG. 1 is a perspective view of a packaging carton, showing our new design;

FIG. 2 is a front view thereof;

FIG. 3 is a rear view thereof;

FIG. 4 is a right side elevation view thereof;

FIG. 5 is a left side elevation view thereof;

FIG. 6 is a top view thereof; and,

FIG. 7 is a bottom view thereof.

The broken lines shown in the Figures depict portions of the packaging carton that form no part of the claimed design.

1 Claim, 6 Drawing Sheets
